UNITED STATES PATENT OFFICE.

ELIJAH M. GODDARD, OF HOLYOKE, MASSACHUSETTS.

GAS-REGULATOR.

SPECIFICATION forming part of Letters Patent No. 328,480, dated October 20, 1885.

Application filed August 31, 1885. Serial No. 175,725. (No model.)

To all whom it may concern:

Be it known that I, ELIJAH M. GODDARD, a citizen of the United States, residing at Holyoke, Hampden county, State of Massachusetts, have invented a new and useful Improvement in Gas-Regulators, of which the following is a specification.

My invention relates to that class of regulators adapted to be interposed between the meter and the service-pipe and in which the operation of a valve is governed by a partially-submerged balloon-float to which it is attached; and my improvements consist in the combination and construction as hereinafter described, and more particularly pointed out in the claims.

My invention is fully illustrated in the accompanying drawings, in which Figure I is a vertical section through the center of the device. Fig. II is an enlarged side view of the valve with a portion of the stem connected thereto. Fig. III is a plan of the top of the valve with a part of the valve-stem, and Fig. IV is an enlarged detail view.

25 A is a case for containing the glycerine or other fluid, in which is partially submerged the float B.

C is a tube superimposed to the valve-casing, and having its upper end above the highest level of the glycerine.

D is a valve-casing, preferably in the form of a globe, having pipe-orifices upon opposite sides, through the one d of which the gas enters the casing from the meter, and through

35 the one d' of which it passes to the burners.

The casing D is divided by a diaphragm, E, provided with a valve-opening, e, in a vertical line with the lower open mouth of tube C, and approximately of the same size. Below diaphragm E, and parallel to it, is a diaphragm, F, having an opening, f, directly below the one e and coinciding with it in size. The opening f is beveled below outwardly, as seen in Fig. I, to form a valve-seat.

45 G is a chamber below diaphragm F, and having a bottom, H, sufficiently removed from diaphragm F to permit a vertically-moving valve to play between them.

h is a port opening into chamber G from casing D upon the side of diaphragm E toward the exit d'.

I is a cup-shaped valve adapted to play be-

tween the diaphragms E F, and close the openings e f.

J is a valve-stem flexibly connected to the top of valve I at one of its ends, and attached at its other to the central top of float B, and extending longitudinally, as shown in Fig. I, through the center of tube C; and K is an adjustable cap to the top of tube C, and at the same time a guide to valve-stem J.

In a gas-pressure regulator there is nothing new in the combination of a case, balloon-float, valve-stem, and valve operating through a diaphragm in a globe below said float and its receptacle, and I make no claim to such; but in my device the valve-stem J is flexibly attached to the top of the peculiar-shaped valve I, which is adapted by the diaphragm E F, the valve-seat f, the chamber G, port h, and open-mouth tube C to operate automatically and sensitively with the slightest increase or decrease in the gas-pressure felt upon either side of diaphragm E, to seat itself and work smoothly independently of any aberration of the float, and by the cap K to the top of tube C serving also as a guide to stem J. The momentum of a jet of gas is prevented from being exerted upon a limited area of the float to give an irregular movement thereto, and is diffused to act only in its lifting capacity upon all of the surface of the float. By the adjustable feature of said cap K the size of the upper mouth of tube C may be changed in effect to govern the sensitiveness of the float to changes in the gas-pressure.

The valve I is a hollow cylinder, closed at its upper end and open at its lower. Upon its lower edge is a beveled valve-face, g, conforming to the seat f in diaphragm F, while its top corner is beveled to cause it always to enter the opening e of diaphragm E, the flexible connection of the stem J to the valve causing said stem to be aligned by the valve itself with the axis of tube C, so that the proper working of the valve is independent of any oscillation of the float B. The length of the valve I is proportioned to the space between the diaphragms E F, so that when the orifice e is closed by the top of the valve the one f is also closed by the seat g. The side of the valve works loosely through orifice f, and to prevent downward pressure of gas passing along the sides of the valve into chamber G

and acting upon the flange *g*, and to prevent any degree of vacuum in chamber *G*, a port, *h*, is formed into the globe *D*, as shown, which, when the valve is entirely closed, permits a pressure beneath it equal to that in the pressure-column of tube *C*, and which pressure, by the escape of gas to the burners, is reduced with that in the tube *C*, so that the valve *I* remains always balanced.

10 The bottom *H* is at such distance from the diaphragm *F* as to stop the top of the valve from leaving said diaphragm.

To form a convenient flexible connection of stem *J* to valve *I*, the lower end of stem *J* is formed into a ball, *i*, truncated upon opposite sides and let into a socket, *m*, in the top of the valve, having walls corresponding to the flat sides of ball *i* and slightly removed from said sides when the ball is in its socket, as seen in Fig. III, so that the valve may oscillate upon said ball, but so that when the valve-stem is rotated by hand the valve also rotates. This is of advantage to permit of gum or foreign substance being cleaned from rim *g* and seat *f*, to insure a perfect seat to the valve, as well as to permit the cylindrical sides of the valve to be cleaned without removing the valve from its casing.

15 A binding-spring or a band, *o*, (shown in section, Fig. I, and in profile, Fig. II, and left off in Fig. III,) incloses the stem, rests on the shoulder formed by the ball *i*, and is fastened at the ends to the top of the valve, so forming a socket-joint, permitting the valve to oscillate, and compelling it to rotate with the stem.

20 The cap *K* consists of a deflecting top, *k*, adapted to extend over the mouth of tube *C* when the cap is in place, a cylindrical body 40 perforated with ports *l*, and a screw-threaded end, *p*. The upper end of tube *C* is correspondingly tapped, and by the milled top *k* the cap *K* is screwed to open the ports *l* to any desired extent.

25 The cap *K* may be made to screw over the tube *C*, if desired, instead of within it, as shown.

Now, having described my invention, what I claim is—

1. The within-described improvement in gas-pressure regulators, consisting of a case, *A*, a partially-submerged float, *B*, a valve-stem operatively connected to said float, and a guide, *K*, within the float for said valve-stem, substantially as shown, in combination with a vertical tube, *C*, open at its lower end, 55 a globe, *D*, two diaphragms, *E* *F*, provided with openings, *e* *f*, and relatively arranged, as shown, a chamber, *G*, with stop *H*, a port, *h*, connecting said chamber with the globe *D*, and a closed top cylindrical valve, *I*, flexibly connected with a valve-stem, *J*, and adapted, as shown and described, to reciprocate to close both diaphragms *E* *F*.

2. In a gas-pressure regulator, the combination, with a case, *A*, a float, *B*, a valve-stem, 65 *J*, and a valve actuated by said float in connection with a diaphragm and globe beneath said float, of a joint consisting of a ball, *i*, upon the end of stem *J*, truncated upon each side, a corresponding socket, *m*, axially arranged in the valve, having flat sides corresponding to those of ball *i* and slightly removed therefrom, as shown and described, and band *o*, arranged, as shown, to hold the ball to the valve.

3. In a gas-pressure regulator, the combination of a closed top partially-submerged float, *B*, and valve connected therewith, a vertical tube, *C*, terminating within said float and provided with side orifices for the passage 80 of gas, and a flange-top, *k*, closing the top of said tube immediately above the gas-orifices therein, perforated to make a guide to the valve-rod, and projecting beyond the side of tube *C* for the purpose, as described, of receiving the 85 momentum of a jet of gas upon a fixed surface and of distributing said gas simultaneously upon all sides of the float.

ELIJAH M. GODDARD.
